UNITED STATES PATENT OFFICE

120,263

DESIGN FOR A TRAILER HITCH

John L. Gilmore, Kansas City, Mo.

Application March 5, 1940, Serial No. 90,686

Term of patent 7 years

To all whom it may concern:

Be it known that I, John L. Gilmore, a citizen of the United States and a resident of Kansas City, in the county of Jackson and State of Missouri, have invented a new, original, and ornamental Design for a Trailer Hitch, of which the following is a specification, reference being had to the accompanying drawing forming part thereof.

I claim:

The ornamental design for a trailer hitch, substantially as shown.

JOHN L. GILMORE.
